DISPENSING STAND FOR A COFFEE CAN

Samuel B. Boster, 7304 Reading Road,
Cincinnati, Ohio 45237

Filed Jan. 25, 1968, Ser. No. 10,302

Term of patent 14 years

U.S. Cl. D44—10

Int. Cl. D7—99

FIG. 1 is a front elevational view showing my new design for a dispensing stand for a coffee can.

FIG. 2 is a side elevational view.

FIG. 3 is a top plan view.

FIG. 4 is a bottom plan view.

I claim:

The ornamental design for a dispensing stand for a coffee can, as shown.
